UNITED STATES PATENT OFFICE.

LEONARD L. RUGGLES, OF WHEATON, ILLINOIS, ASSIGNOR TO RESERVE HOLDING COMPANY, OF KANSAS CITY, MISSOURI, A CORPORATION OF DELAWARE.

TELEPHONE SYSTEM.

Application filed March 17, 1927. Serial No. 175,953.

This invention appertains in general to telephone systems, and it is an object of the invention to provide a system wherein toll calls between near-by cities may be efficiently 5 and quickly established, and wherein a record of the toll calls may be kept in a simple manner.

It frequently happens that within a certain 10 community there is a town served by an automatic telephone system, and a number of near-by towns served by manual systems, and the automatic telephone exchange serves as a switching center for the community in the establishment of the toll connection, each 15 of the manual exchanges being connected to the automatic exchange by toll trunks. It is with such telephone systems that the present invention is concerned, and it is an object of this invention to provide such a telephone 20 system wherein a toll trunk that connects a manual exchange with the automatic exchange may be used in making toll calls within the community as well as toll calls extending outside of the community, 25 the toll connections between the towns within the community being set up automatically and handled on a single ticket basis, and the toll connections to towns outside of the community being set up manually and handled 30 on the usual two ticket basis. These and other objects of the invention will be apparent from the accompanying specification including the three figures of drawings forming a part thereof.

The drawings illustrate one preferred embodiment of the invention. I do not, however, wish to be limited to the precise construction shown, the same being for illustrative purposes only. What I consider new, 40 and desire to procure by Letters Patent is more particularly pointed out in the appended claims.

Referring to the drawings, Fig. 1 is a schematic illustration of the layout of the various exchanges. Figs. 2 and 3 when arranged next to each other show the circuit arrangement whereby the various functions are obtained.

Referring now to Fig. 1, at E is shown 50 a central automatic exchange and at A, B, C, and D are shown manual exchanges of adjacent towns. At M, N, and O are shown toll trunks connecting the town E which is the switching center for the community with 55 distant cities. The towns A, B, C, and D are

rather close to the town E, they may for instance be suburbs of that town, and there may be a considerable amount of traffic not only between the adjacent towns and the town E but also between the towns A, B, C, 60 and D. The exchange at E serves as a switching center in the establishment of connections between subscribers in the respective towns A, B, C, D, and E and also as a switching center in the establishment of connections between the respective towns and the trunk lines M, N, and O leading to more remote cities. In a community such as is here served, although there may be an appreciable amount of toll telephone traffic 70 between the neighboring towns which does not involve subscribers in the town E, still by far the greater percentage of the toll traffic will either originate or terminate in the town E. Since toll connections within 75 the community served by the exchanges A, B, C, D, and E are set up automatically without the aid of the toll operator in the exchange E, the record of the amount to be charged for the calls may be kept by the 80 respective operators in the towns A, B, C, and D, a single record being sufficient. The operator at each of the outlying towns keeps the record of the charges for all outgoing toll calls, and also for all incoming calls 85 from subscribers in the town E.

All incoming and outgoing calls over the long distance toll trunks M, N, and O, for the community pass through the toll operator's switchboard at E.

Referring now to Figs. 2 and 3, there is shown in Fig. 2, a toll trunk 35—36 terminating in a jack J₁ at the operator's switchboard in the exchange A. The operator's switchboard is further provided with a number of jacks, not shown, over which the operator has access to local subscribers' lines, and a number of cords which are used in establishing local connections. For establishing toll connections, any standard toll cord having battery potential on the sleeve may be used. A suitable cord is shown in the patent to Wicks #1,593,737, granted July 27, 1926. The jack J₁ is connected through a repeating coil R₁ in the exchange A to the toll trunk 35—36 and the latter is connected by means of a second repeating coil R₂ in the exchange E to a toll selector repeater TS.

In Fig. 3, there is shown at P an automatic subscriber's station in the town E. The sub-

scriber's line may be connected by means of a line switch LS, to any one of a number of first selectors such as S_1 , the selectors being of the well known Strowger automatic type. 5 The contacts in the banks of the first nine levels of the selector repeater TS are multiplied with the corresponding contacts in the first nine levels of the first selectors such as S_1 and lead to the second selectors such as 10 S_2 . The bank contacts in the tenth level of the first selectors lead as usual to the toll recording position. The second selectors such as S_2 have access to connectors such as C, which connectors in turn each have access 15 to one hundred subscribers' lines in the town E. The second selectors such as S_2 and the connectors such as C are also of the well known Strowger type. The bank contacts in the tenth level of the toll selector TS are 20 multiplied with the corresponding contacts in certain second selectors of which S_2 is one, and lead to a number of rotary connectors of which only one, RC, has been shown. The rotary connectors may be of the type shown 25 at H in Fig. 2 of the patent to Jacobsen, Number 1,349,381, granted August 10, 1920. The rotary connectors have access to the toll trunks connecting the exchange E with exchanges in the towns A, B, C, and D. The 30 connection to the trunk leading to the exchange at A is shown.

A branch from the trunk connecting the exchange at A with the exchange at E leads to a jack J_2 at the toll operator's switchboard in the latter exchange. The toll switchboard at E is provided with a number of such jacks connected to the trunks extending to the other towns B, C, and D, and likewise with a number of jacks terminating the 40 long distance trunks M, N, and O. The toll operator at E is provided with a number of cord circuits for establishing connections between the jacks in her switchboard. Any standard toll cord having battery potential 45 on the sleeve may be used. A suitable cord is shown in Fig. 1 of the patent to Wicks above referred to. The toll operator at E is also provided with the usual toll service trunks whereby she may set up a connection 50 to an automatic subscriber's line in the town E and connect that line to the jack of one of the lines M, N, or O. It is apparent that she may, if necessary, connect the automatic subscriber's line with a trunk leading to the 55 towns A, B, C, or D.

It will be assumed that the operator at A has received a call for subscriber's line in the town E. She thereupon inserts the plug of one of the toll cords at her switchboard into a jack such as J, which terminates a trunk leading to the town E and operates the dial key DK preparatory to operating the automatic switches in the exchange E. It is of course understood that the other end 60 of the cord circuit is connected to the call-

ing subscriber's line. The relay 50 operates over a circuit from battery at the sleeve of the cord extending through the lower front contacts on the dialing key DK. At contacts 52 relay 50 establishes a holding circuit 70 for itself independent of the dialing key, and at contacts 51 it prepares a holding circuit for the automatic switches. The operation of the key DK causes the supervisory relay 60 and the relay 100 to operate in series 75 over a circuit extending from battery at the relay 100, through the upper winding of the relay, back contacts 81 of relay 80, conductor 72 to the mid point of the left-hand side of the repeating coil R_2 , 80 thence through conductors 35 and 36 connecting the two exchanges, to the mid point of the right-hand windings of the coil R_1 , thence through the realy 60, front contacts 85 16 of the jack J_1 , front contact 17 of the dialing key, to ground at the pulsing contacts of the sending device. Relay 60 at its front contacts 61 closes a circuit for the supervisory lamp L, while the realy 100 at its front contacts 102 establishes a circuit for the relay 110. Relay 110 at contacts 112 places ground upon the test conductor 46 rendering the trunk 44-45 busy at the banks of the rotary connectors, and at front contacts 113 it prepares the circuit for the vertical magnet VM of the toll selector repeater TS, at contacts 112 a circuit is also established for the right-hand winding of shunt field relay 80. Relay 80, is, however, so constructed that before it can operate 100 current must be flowing through the two windings so as to produce fluxes in opposite directions. The relay 80 therefore does not operate at this time. Relay 140 operates over the test conductor 46 which is grounded at 105 contact 112, and at its contact 144 establishes a circuit for the relay 150 and for the visual V. The visual indicates to the toll operator the busy condition of the trunk leading to the exchange A. The operator at A now proceeds to dial the first digit of the subscriber's number. With each interruption produced by the calling device in the circuit of the relay 100, the spring 102 falls back and establishes a circuit for the vertical magnet in 110 series with realy 120, by way of back contact 93 and front contact 113. Relays 110 and 120 being slow acting remain operated during the series of impulses. The vertical magnet moves the wipers of the toll selector 115 in a step-by-step manner to bring them opposite the desired level of the outgoing trunks. When the vertical magnet takes its first step, the off-normal contacts 125 close and establish a circuit for the relay 130 by way of front contact 121 of relay 120 to ground at the front contact 112 of relay 110. Relay 130 operates and at contacts 131 establishes a locking circuit for itself by way 120 of the interrupter contacts 145 of the rotary 130

magnet R, and at contact 132 prepares a circuit for the rotary magnet. Upon the cessation of the impulses the relay 120 falls back, and at the back contact controlled by 6 the armature 121 completes a circuit for the rotary magnet from ground at the front contact 112, back contact 121, and front contact 132 of the relay 130. The rotary magnet R takes one step moving its wipers 151, 10 152, and 153 opposite the first set of contacts on the bank. At contact 145 the rotary magnet opens the locking circuit for the relay 130 which relay thereupon releases. The further operation of the rotary magnet will 15 now depend upon whether the wiper 152 is resting upon the bank of a busy or an idle trunk. Assuming that the trunk is busy and therefore there is ground potential upon the bank with which the wiper 152 is in contact, 20 there is established an operating circuit for the relay 130 as follows: from ground at the wiper 152, through back contact 92 of relay 90, back contact 145 of the rotary magnet R, vertical off-normal contact 125, through 25 the relay 130, to battery and ground. Relay 130 therefore operates a second time and at its contact 132 again establishes the circuit for the rotary magnet R, which magnet again operates, and again opens the circuit for the 30 relay 130 at its armature 145, and also moves the wipers 151 and 153 opposite the next trunk in the level. This continues until the bank of an idle trunk is reached. It is to be noted that when the wiper 152 is in 35 contact with a grounded bank terminal, the relay 90 is short circuited from ground at armature 112 extending to one side of the relay, and ground at the wiper 152 extending to the other side of the relay by way of 40 back contact 92 of said relay. When an idle trunk is reached, the wiper 152 does not find ground potential and therefore no circuit is established for the relay 130 as previously traced. The relay 90 is now not 45 short circuited, and there is established a circuit for the relay 130 and the relay 90 in series, said circuit extending from grounded battery at relay 130, off-normal contacts 125, back contact 145 of rotary magnet, lower terminal of relay 90, through the 50 relay, to ground at front contact 112 of relay 110. Relay 130 can not operate over this circuit due to the high resistance of relay 90, which latter relay however operates. 55 The opening of back contact 92 of relay 90 opens the previous short circuit around the relay 90, and at the front contact 92 the said relay extends ground from the front contact 112 of relay 110 to the wiper 152, thereby 60 immediately rendering the seized trunk busy to other toll selectors. At contacts 91 and 94, relay 90 completes a loop across the wipers 151 and 153, said loop extending from the wiper 151, through front contacts 101 65 and 91, the upper right-hand repeating coil R₂, back contact 71 of relay 70 and front contact 111 of relay 110, through the left-hand winding of relay 80 to the lower right-hand winding of the repeating coil R₂, thence through the lower talking conductor 43 and 70 through front contact 94 to the wiper 153. Assuming that the wipers 151 and 153 are resting upon the banks of the trunk 154, 156, which happens to be the first idle trunk reached, the closed loop previously traced 75 extends over said conductors to the second selector S₂. This closed loop causes the operation of the usual relays in the selector S₂ preparing that selector to receive the next group of impulses. The relay 80 does not 80 operate its contacts over the above traced loop although both windings are at this time energized, due to the fact that the current is flowing in the wrong direction in the left-hand winding of the relay. 85

The operator at A now operates the calling device S in accordance with the next digit in the wanted subscriber's number. With each interruption at the calling device the circuit for the relay 100 is again opened and the relay 100 falls back each time. At this time the previously traced circuit for the vertical magnet of the toll selector repeater TS is open at the front contact 93 of the relay 90. With each interruption in current 90 at the calling device the contacts 101 open and break the previously traced closed loop across the wipers 151 and 153 thereby causing the step by step operation of the vertical magnet in the second selector S₂ in the well known manner. The second selector S₂ operates in the usual manner to extend the connection to an idle connector in the selected group of connectors. The operator at A then 95 operates her calling device in accordance with the last two digits in the wanted subscriber's number, thereby operating the selected connector C in the usual manner to extend the connection to the line P. 100

The operator at A having dialed the last digit now restores the dialing key DK. This is of no effect at this time in so far as the automatic switches are concerned since the circuit for the relay 100 and the relay 60 is now maintained from ground at the contact 105 51 of relay 50 extending by way of the back contact of the dialing key now restored to the front contact 16 of the jack J₁. 110

If the called line happens to be busy the connector operates in the usual manner to apply a busy tone current to the talking conductors of the calling line, said current being repeated by way of the repeating coils R₂ and R₁ to the calling party. If the called 115 line is idle the connector operates to apply 120 ringing current to said line to signal the subscriber thereat. Upon the answering of the call by the called subscriber the usual relay in the connector operates to reverse the current over the talking conductors extend- 125 130

ing to the repeating coil R_2 . The reversed current in the bridge including the left-hand winding of the shunt field relay 80 causes the relay to operate. Relay 80 at its 5 front contact 82 establishes a circuit for the lower winding of the relay 100 thereby maintaining said relay operated. At contacts 81, relay 80 opens the initial circuit for the upper winding of the relay 100 and extends 10 the conductor 72 to the grounded relay 70. Relay 70 does not operate at this time because the conductor 72 is also grounded at the other end by way of the sending device S before the key DK is restored, and at contact 15 51 after the key is restored. The relay 60 being deprived of battery through upper winding of relay 100 releases and extinguishes the supervisory lamp L. The parties may now converse.

20 If the called party terminates the call first, the battery connection to the line is reversed at the connector causing the release of relay 80. At contacts 82, relay 80 opens the circuit for the lower winding of the relay 100, 25 and at its upper contacts 81 reestablishes the previously traced circuit for the upper winding of the relay 100 in series with the relay 60, ground being received by way of front contact 51 and the back contact of the key DK instead of through the contact 17 30 and the contacts of the sending device S. The relay 100 is maintained operated thus maintaining the toll selector TS in position. At contact 61 relay 60 closes the circuit 35 for the supervisory lamp L thereby indicating to the operator at A that the called party has terminated the call. If the calling party has not at this time also terminated the call, the operator at A may converse with 40 that party and determine if the connection has been completed and if it has not been completed she may again set up the connection to rering the line P. If the call has been completed the operator at A removes 45 the plug from the jack J_1 thereby causing the release of the relay 50, and the connection of battery potential at the back contact 16 of the jack J_1 to short circuit the relay 60 and the relay 100. When this happens 50 the relay 60 drops back as does also the relay 100. Relay 100 at its contact 102 opens the circuit for the relay 110. The relay 110 falls back and at contact 112 releases relay 90, 55 which relay completes at contact 93 a circuit for the release magnet RS, said circuit extending from grounded battery at the release magnet through the off-normal contacts 95, and back contacts 113, 93, and 102 to ground. This causes the release of the selector. The release of the selector S_2 and the connector C takes place in the usual 60 manner upon the opening of the loop across the talking conductors at contact 101.

If the calling party should replace the 65 receiver before the called party does, the

operator at A getting the customary signal in the cord circuit connected to J_1 causes the release of the train of automatic switches by withdrawing the plug from the jack J_1 . When the plug is withdrawn from the jack 70 the relay 50 ceases to receive battery from the sleeve of the jack and falls back. At the back contact 16 of the jack battery potential is placed upon the conductor extending to the relay 60 and through the repeaters to the conductor 72 in the toll selector. This battery potential extends by way of conductor 72 and front contact 81 of relay 80, which relay is still in its 75 operated position due to the fact that the called party has not terminated the call, to ground by way of the relay 70. Relay 70 operates, and at its contact 73 establishes a locking circuit for itself by way of off-normal contacts 95 to battery through the 80 release magnet. The release magnet does not operate over this circuit due to the high resistance of the relay 70. At contact 71 relay 70 opens the circuit for the left-hand winding of the shunt field relay 80 thereby 85 causing the release of said relay. Relay 80 at front contact 82 opens the circuit for the lower winding of relay 100 but at its back contact 81 does not again establish a circuit for the upper winding of the relay 90 100 because the conductor 72 is at this time connected to battery instead of to ground. Relay 100 thereupon falls back and is followed by relays 110 and 90, thereby causing the release of the selector in the previously 95 described manner. Upon the opening of the off-normal contacts 95 relay 70 also releases. The selector S_2 and the connector C were 100 released in the customary manner when the relay 70 at contact 71 opened the direct 105 current bridge across the wipers 151 and 153.

An explanation will now be given of the manner in which a subscriber at the automatic exchange E may extend a connection 110 to the operator's position at A to call a party in that exchange. Upon the removal of the receiver at the station P, the line-switch LS operates in the well known manner to extend the line to an idle first selector, such as 115 S_1 . The subscriber at P now dials the first two digits of the number assigned to the exchange A, causing the operation of the first selector S_1 and then the second selector S_2 to extend the line to one of a number of rotary connectors RC. The last level of certain second selectors such as S_2 is assigned to 120 rotary connectors RC instead of to the usual connectors C. The banks of the rotary connector RC lead to the various adjacent 125 towns such as A, B, C, and D, shown in Fig. 1. The subscriber now dials the next digits of the number assigned to the exchange A thereby operating the connector in the manner explained in connection with the 130

rotary connector shown at H in Fig. 2 of the patent to Jacobsen 1,349,381 granted August 10, 1920. When the wipers of the rotary connector come to rest on a trunk such as 44—
 5 46 leading to the exchange A, which it will be assumed is the first idle trunk reached, ground potential is applied to the conductor 46 at the test wiper of the rotary connector in the manner explained in the above referred to patent. This ground potential automatically renders that trunk busy to other rotary connectors. Cut off relay 140 operates from grounded conductor 46 and at contacts 144 establishes a circuit for the relay 150 and for the visual V. Relay 150 operates its contacts 151 to short circuit the drop 170. The visual indicates to the operator the busy condition of the trunk leading to exchange A. A moment later the rotary connector RC operates to project ringing current over the talking conductors 44, 45. The ringing current does not operate the drop 170 due to the open contacts 143. The ringing current is projected by way of the conductors 44, 45, to the repeating coils R_2 and is there repeated to the repeating coils R_1 . A circuit is then established by way of the left-hand windings of the repeating coils R_1 through the back contacts 30 of the jack J_1 to the drop 15 at the operator's position at A. The drop operates and at its contacts 14 establishes a circuit for the relay 50 which at its contacts 51 prepares a circuit for the relay 100, and at contact 52 prepares a locking circuit for itself. The operator at A, noting the condition of the drop, inserts the plug of a cord circuit into the jack J_1 . The relay 50 is maintained operated over the sleeve of the jack J_1 . A circuit 40 is also completed for the relay 100 and the relay 60 as previously traced. Relay 100 operates, and establishes a circuit for the relay 110 which relay also operates. At contacts 111, relay 110 establishes a direct current loop across the talking conductors 44, 45 leading to the rotary connector RC, said loop extending from the wipers of the rotary connector RC through the conductors 34, 45, the right-hand repeating coils of R_2 , 45 thence being completed by way of back contact 71 of relay 70, front contact 111, and the left-hand winding of relay 80. This causes the cutting off of the ringing current at the rotary connector RC. The current flowing in the above traced loop is in the proper direction to cause the operation of the relay 80. Relay 80 at its front contact 82 establishes a holding circuit for the relay 100 through its lower winding, and at 55 81 shifts the conductors 72 to the grounded winding of the relay 70. The relay 60, the upper winding of relay 100, and relay 70 are now deenergized, their circuits being the same as previously traced when relay 80 operated. The operator at A may now con-

verse with the calling party at P and determine the number wanted. She then extends the connection to the desired line.

Upon the termination of the call by the calling party the selectors S_1 and S_2 and the rotary connector RC are released in the usual manner. Upon the release of the rotary connector, battery and ground are removed from the talking conductors 44, 45, thereby causing the release of the contacts 75 controlled by the shunt field relay 80. At contact 81, relay 80 again establishes a circuit including the upper winding of relay 100 and the relay 60 in series. The operator at A noting the lighted condition of the lamp L pulls down the connection. When this is done the relay 100 releases in a manner previously pointed out, thereby causing the release of relay 110 which relay at its contact 80 112 removes ground from the conductor 46 causing the release of cut-off relay 140, which in turn causes the release of relay 150 and of the visual V. The operator at J_2 noting the released condition of the visual now knows that the line 44, 45 is not busy. 85 The relay 150 opening its contact 151 removes the short circuit from across the drop 170 thereby again allowing the operator at A to call the operator at E should she so desire. Upon the removal of the plug from 90 the jack J_1 the relay 50 falls back, its circuit being broken at the sleeve of the jack. All the relays having restored, the circuits are now again in their initial condition.

From the above description it is now apparent that the operator at A may automatically call the operator at B, C, or D by operating the toll selector repeater TS to its tenth level and then operating the rotary connector RC which is seized, to extend the 100 connection to the near-by town.

When it is desired to extend a connection from a toll line such as M, N, or O, to one of the adjacent towns, the toll operator at E may call the operator at A, B, C, or D, by 110 inserting the plug of a cord circuit into a jack such as J_2 , terminating a trunk leading to the desired town and then projecting ringing current over the talking conductors. Battery from the sleeve of the plug on the 115 cord causes the operation of relay 160, which relay at contact 161 makes the conductor 46 test busy, and also causes the operation of relay 140 and also relay 150. The ringing current projected over the talking conductor causes the operation of drop 15 in the same manner as was previously pointed out. It is of course understood that the cord inserted in the jack J_2 is at its other end connected to the toll line such as M, N, or O over which 120 the call was received.

For the sake of further explaining the operation of the system it will now be assumed that the operator at A has received a toll call 125 for a point outside of the community, that is,

for a call that must be sent over one of the toll lines, M, N, or O. The operator at A now, as before, inserts the plug of one of the toll cords at her switchboard into a jack such as J_1 which terminates a trunk leading to the town E, but now instead of operating the dial key DK as before, she operates a ringing key to project ringing current over the talking conductor of the cord circuit. Ringing current is sent through the left-hand coils of the repeating coil R_1 at the exchange A and is repeated at the right-hand coils of the repeating coil R_2 which is located in exchange E. A circuit is then established for the drop 170 by way of conductors 44-45, 141-162, the back contacts on the jack J_2 and the back contact 143 of relay 140. The drop 170 operates and at contacts 171 places ground upon the test conductor 46 leading to the rotary connector, thus busying the trunk to incoming calls. The ground at 171 further completes a circuit for the cut-off relay 140, which relay, at its contact 143, opens the circuit for the drop, and at contact 144 establishes an operating circuit for the visual V and for the relay 150. The drop 170 is of the type that must be manually restored. This may be done mechanically when a plug is inserted into the jack J_2 . The relay 150 further short circuits the drop. The operator in the exchange E noting the condition of the drop inserts the plug of a cord circuit into the jack J_2 . Any standard toll cord circuit having battery on the sleeve may be used. Upon the insertion of the plug into the jack, relay 160 operates from battery at the sleeve of the jack, and at contacts 161 maintains the ground upon the test conductor 46 so that although the drop is restored upon the insertion of the plug into the jack J_2 , the relay 140 will not restore. The toll operator at E may now converse with the operator at A. The operator at E then extends the connection over a trunk such as M, N, or O, as instructed, in the usual manner.

Upon the termination of the call the respective operators receive the customary signal from their cord circuits and take down the connection. When the plug is removed from the jack J_2 the relay 160 releases and at contacts 161 removes ground from the test conductor 46 thereby causing the release of relay 140, and further removing the busy guarding potential from the bank of the rotary connectors. Relay 140 upon dropping back opens the circuits for the relay 150 and for the visual, which a moment later restore.

It is now apparent that if, due to temporary disorders, it is impossible to dial over a trunk connecting the town E with one of the adjacent towns, A, B, C, or D, while it is possible to talk over that trunk, toll connections from the towns A, B, C, or D, to points within the switching community may

be handled by the toll operator at E. Under these conditions the operator in one of the towns A, B, C, or D would project ringing current over the talking conductors of the trunk leading to the town E to call the toll operator at E. The operator at E would then extend the connection by means of a cord circuit to the trunk leading to an adjacent town, or by means of the usual toll service trunk set up a connection to the wanted subscriber's line if the call is for an automatic subscriber in the town E.

Before concluding the description, it may be well to explain the purpose of the slow acting relay 150 and the contacts 143 of the relay 140. With reference to this matter, it is to be noted that when the trunk 35-36 is in use in connection with the automatic switches in the exchange E, battery and ground potential are applied to the two talking conductors 42-43 by way of the automatic switches, and the condenser between the right hand repeating coils R_2 is short circuited. At this time relays 140 and 150 are energized, therefore the drop 170 is short circuited at 151, and is disconnected from the talking conductors at 143. Upon the termination of the call by the operator at A, the short circuit across the condenser is removed. The condenser is then charged by the potential across the talking conductors. A moment later the automatic switches release, leaving the condenser in the charged condition, and then the relays 140 and 150 restore. After the relay 140 has released and before the release of the relay 150, the talking conductors 42-43 are short circuited by way of conductor 141, back contact at the tip of jack J_2 , back contact 143, and front contact 151, back contact at the ring side of jack J_2 , conductor 162, thence through conductor 44 to conductor 43 and the lower side of the right-hand repeater R_2 . This offers a discharge path for the condenser in the right-hand repeating coil R_2 . The drop 170 is short circuited at front contact 151. When the relay 150 releases and reconnects the drop to the talking conductors the condenser will have been discharged. Thus there is no possibility of the drop 170 being operated by a discharge from the condenser.

Having described my invention, what I consider new and desire to procure by Letters Patent is:

1. In a telephone system, a trunk terminating at one end at an operator's switchboard in a manual exchange, and at the other end in an automatic exchange, directly operated automatic switches at the automatic exchange having access to the trunk, a relay at the end terminating at the switchboard arranged to be operated responsive to the seizure of the trunk by an automatic switch, means effective responsive to

the operator at the manual exchange answering the incoming call to lock the relay in its operated position and to establish a direct current loop across the end of the 5 trunk terminating in the automatic exchange.

2. In a telephone system, a trunk including two talking conductors terminating at one end at an operator's switchboard in a 10 manual exchange, and at the other end in an automatic exchange, a signal, a dialing key, and a relay, at the end of the trunk which terminates at the operator's switchboard, means for operating the signal for 15 indicating to the operator an incoming call, means for locking said relay in its operated position when the call is answered, means effective responsive to the locking of the relay in its operated position for establishing 20 a direct current path across the end of the trunk in the automatic exchange, an additional circuit including the dialing key for operating the relay responsive to the operator initiating a call over the trunk 25 line, automatic switches at the automatic exchange operated over the trunk line, and a circuit controlled by the relay for maintaining the switches operated.

3. In a telephone system a trunk line, a 30 condenser bridged across the talking conductors at one end thereof, a signal connected across the trunk to be operated thereover, and means effective upon the termination of a call over the trunk to momentarily provide 35 a discharge path for the condenser exclusive of the signal, thereby preventing the signal from being operated by the condenser discharge.

4. In a telephone system a trunk line, a 40 condenser bridged across the talking conductors at one end thereof, a signal connected across the trunk to be operated thereover, means for disconnecting the signal from the line when the line is in use, and means effective upon the termination of a call over 45 the trunk to momentarily provide a discharge path for the condenser exclusive of the signal, thereby preventing the signal from being operated by the condenser discharge.

5. In a community telephone switching system wherein there are a number of manual telephone exchanges each connected by a toll trunk to a central automatic exchange 55 which constitutes the switching center for the community, an automatic switch accessible to and having access to the toll trunks, a local selector in the automatic exchange having access to the automatic 60 switch, and means controlled over the toll trunks for seizing said local selector.

6. In a telephone system wherein an automatic exchange serves as a switching center in the establishment of toll connections 65 to and from manual exchanges in near-by

towns, toll trunks connecting each of the manual exchanges with the automatic exchange, local subscribers' lines terminating in the automatic exchange, a selector, means controlled over any local subscriber's line 70 for connecting the subscriber's line to the selector, means controlled over the toll trunk for connecting the toll trunk to the selector, and automatic switches having access to the local subscribers' lines and to the toll 75 trunks accessible to said selector.

7. In a telephone system wherein an automatic exchange serves as a switching center in the establishment of toll connections to and from manual exchanges in near-by towns, 80 toll trunks connecting each of the manual exchanges with the automatic exchange, automatic switches for extending local connections between subscribers of the automatic exchange, an automatic switch having access 85 to said toll trunks, and means in the automatic exchange for extending a connection from a toll trunk to said last named automatic switch over either of two paths, one of the paths including at least one of the 90 first mentioned automatic switches and the other path excluding all of the first mentioned switches.

8. In a telephone system wherein an automatic exchange serves as a switching center 95 in the establishment of toll connections to and from manual exchanges in near-by towns, toll trunks connecting each of the manual exchanges with the automatic exchange, automatic switches for extending local connections between subscribers of the automatic exchange, an automatic switch having access to said toll trunks, means in the automatic exchange for extending a connection 100 from a toll trunk to said last named automatic switch over either of two paths, one of the paths including at least one of the first mentioned automatic switches and the other path excluding all of the first mentioned switches, a toll operator's switchboard 110 in the automatic exchange, and a branch from each toll trunk terminating at the switchboard.

9. In a telephone system, a manual telephone exchange, an automatic telephone exchange, a trunk line connecting the two, said trunk line terminating in an operator's switchboard in the manual exchange and in an automatic switch at the other exchange, a branch at the automatic exchange connecting the trunks to an operator's switchboard in that exchange, means at each operator's switchboard whereby either operator may call the other over the trunk line, means whereby the automatic switch may be controlled over the trunk line from the operator's switchboard at the manual exchange, and means controlled from an automatic subscriber's station to extend an automatic subscriber's line over the trunk line 130

to the operator's switchboard in the manual exchange.

10. A community telephone switching system comprising an automatic telephone exchange, a plurality of neighboring manual telephone exchanges each in a different neighboring town, toll trunks connecting each of the manual exchanges with the automatic exchange and terminating each in an automatic switch at the last named exchange, a branch extending each toll trunk to a toll operator's switchboard in the automatic exchange, means whereby either operator may call the other over the toll trunk, and automatic switches in the automatic exchange controlled over a toll trunk or over a local subscriber's line to extend connections to a subscriber's line or to a toll trunk at will.
11. A community telephone switching system wherein an automatic telephone exchange serves as a switching center in the establishment of toll connections to and from manual exchanges in near-by towns within the community, toll trunks connecting the manual exchanges with the automatic exchange, automatic switches in the automatic exchange automatically accessible to the trunks and also having access to the trunks, a toll operator's switchboard in the automatic exchange, a branch from each trunk terminating at said switchboard, and toll lines extending outside of the community also terminating at said switchboard.

12. A community telephone switching system wherein an automatic telephone exchange serves as a switching center in the establishment of toll connections to and from manual exchanges in near-by towns within the community, toll trunks connecting the manual exchanges with the automatic exchange, automatic switches in the automatic exchange automatically accessible to the trunks and also having access to the trunks, said automatic switches including a local selector, a toll operator's switchboard in the automatic exchange, a branch from each trunk terminating at said switchboard, and toll lines extending outside of the community also terminating at said switchboard.

13. In a community telephone switching system wherein an automatic telephone exchange serves as a switching center in the establishment of toll connections to and from manual exchanges in near-by towns within the community, toll trunks connecting the manual exchanges with the automatic exchange, toll lines connecting the automatic exchange with points outside of the community, and means whereby toll calls within the community may be handled on a sin-

gle ticket basis, and toll calls extending outside of the community may be handled on a two ticket basis, said means comprising means for automatically setting up toll connections between the towns within the community by way of said automatic exchange without the aid of an operator in the automatic exchange, and means whereby the operator in the automatic exchange may set up toll connections between the toll lines and the toll trunks.

14. In a telephone system, a trunk line one end of which has two branches, a condenser in the portion of the trunk circuit common to those branches, signalling means in one of the branches normally connected across the condenser and operated from the other end of the trunk line, a connector having access to the other branch of the trunk line, a shunt circuit, means responsive to the answering of a call extended over the trunk line by the connector for rendering said signalling means inoperative and for connecting the shunt circuit across the condenser, means responsive to the called party disconnecting first for opening the shunt circuit, whereby the condenser becomes charged, and means for discharging the condenser when the connector releases and before the signalling means again becomes operative, whereby the operation of the signal by a condenser discharge is prevented.

15. In a telephone system, an automatic exchange, a trunk line one end of which terminates at said exchange, a condenser, signalling means at said exchange bridged across said condenser and operative responsive to the application of alternating current to the other end of said trunk line, automatic switches at said exchange, means responsive to digit impulses transmitted from said other end of the trunk line for operating the switches to extend a connection, said condenser being in the talking circuit, means responsive when a call is so extended for rendering the signalling means inoperative, a shunt circuit around said condenser during the connection, means for opening said shunt circuit if the connection is released before the called party disconnects, whereby the condenser becomes charged, and means for discharging the condenser when the release takes place and before the signalling means is restored to normal condition, whereby the operation of the signal by a condenser discharge is prevented.

In witness whereof, I hereunto subscribe my name this 10th day of March, A. D. 1927.

LEONARD L. RUGGLES.
